UNITED STATES PATENT OFFICE.

RAYMOND T. PIERCE, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL SYSTEM FOR ELECTRIC FURNACES.

1,367,089.

Specification of Letters Patent.

Patented Feb. 1, 1921.

Application filed December 14, 1918. Serial No. 266,688.

To all whom it may concern:

Be it known that I, RAYMOND T. PIERCE, a citizen of the United States, and a resident of Wilkinsburg, in the county of Allegheny and State of Pennsylvania, have invented a new and useful Improvement in Control Systems for Electric Furnaces, of which the following is a specification.

My invention relates to control systems for electric furnaces and it has particular relation to the control of those furnaces in which a negative temperature coefficient exists during the operation thereof.

In furnaces of the character designated, it is necessary to maintain a substantially constant temperature after the initial setting, the temperature depending upon the character of work being done, the time of firing, etc. It is a matter of more or less difficulty, in such furnaces, to maintain the desired temperature and, at the same time, have available a simple and compact means for preventing an excessive overload upon the furnace and the subsequent burning-out thereof. It is obvious, of course, that some danger will always exist in furnaces of the type described because of the negative temperature coefficient obtaining therein. That is, as the furnace becomes hotter, the resistance thereof tends to decrease, and the current passing through the furnace, therefore, increases.

I, therefore, arrange a control system in which I employ a minimum number of switching arrangements to accomplish the desired control, and, at the same time, I so associate these switches with a safety interlocking member that the burning out of the furnaces, by reason of an excessive over-load being imposed thereon, will be prevented.

Another object of my invention is to provide a positive current-controlled element which shall operate to limit the current passing through the furnace.

For a better understanding of my invention, reference may be had to the accompanying drawing, the single figure of which illustrates a control system constructed in accordance with my invention. A furnace 1, is shown as supplied with power from a secondary member 2 of a transformer 3, the primary member of which is connected to any suitable source of energy.

The secondary winding 2 of the transformer 3 is provided with spaced taps 4, 5 and 6, these taps being so associated with the winding that the number of effective turns thereof which are used to feed power to the furnace may be varied in accordance with the control desired.

The control elements are embodied in a graphic-ammeter arrangement which comprises electro-dynamometer elements 7 and 8 controlling the rotation of a motor 9, the motor 9 being provided with a worm-threaded shaft 10.

The manner in which a recording ammeter, of the type designated, operates is set forth in numerous U. S. patents, the best showing probably being that of U. S. Patent No. 1,010,160, issued to the Westinghouse Electric & Manufacturing Company, November 28th, 1911, on an application filed by Paul MacGahan. In that patent is set forth the manner in which the control circuits are associated with a Kelvin balance, the movable member of which is adapted to make contact between two terminal points in such way that a motor is constrained to run in the one or the other direction. However, the structure shown in that patent contemplates the use of a continuously operating motor, and means are provided whereby the recording mechanism is engaged by, and disengaged from, the continuously rotating worm shaft upon which the motor is mounted. In the present application of the Kelvin balance, recording-ammeter structure, I contemplate the use of a motor which is operated in the one or the other direction by the coaction of the movable arm of the aforescribed balance system, and, in place of the recording pen, I use an engaging element which actuates switches to control the amount of voltage supplied to the furnace, all of which is hereinafter described in detail. The members 7 and 8 are energized, in accordance with the current passing through the furnace, by means of a current transformer 11 disposed in one of the leads passing from the secondary winding of the transformer 2 to the furnace.

A movable member or carriage 12 is mounted upon the worm-threaded shaft 10 and is adapted to move along the same. The carriage 12 is provided with a lug 13 which is adapted to engage and operate certain

switches in a manner hereinafter to be described. A terminal member 14 is shown as providing a contact with a companion member 15 upon the carriage 12.

5 Magnetically controlled switches 16, 17 and 18 control the number of effective turns which are used upon the secondary winding 2 of the transformer.

A control circuit 19, which supplies power 10 to operate the switches 16, 17 and 18, is associated therewith and with three-point switches 20 and 21, the actuation of which so changes the control circuits that the switches 16, 17 and 18, hereinbefore described, are 15 operated to vary the desired number of effective controls existing upon the transformer secondary 2.

It will be noted that the three-point switches 20 and 21 are provided, respectively, with biasing springs 22 and 23, thus making their action more positive and satisfactory. A member 24 is adapted to operate the switching levers of the switches 20 and 21 through engaging pin members 25, 26, 27 25 and 28 in a manner hereinafter described.

Having described a control system constructed in accordance with my invention, the operation thereof is as follows:

Assuming that the main-line switch to the 30 furnace 1 has been closed and, moreover, that the control circuit has been energized, a circuit will be completed through the energizing coil of the switch 16. The closure of the switch 16 causes a maximum number of 35 effective turns to be active in supplying power to the furnace, and the current passing through the furnace will, therefore, be of large value. As the furnace heats up, however, the resistance thereof decreases, 40 since it possesses a negative temperature coefficient and, therefore, the current passing through the furnace will increase more than is desired. This increase of current, by its action upon the current transformer 11, 45 will cause the motor 9 to rotate and the member 12 to travel along the worm-threaded shaft 10.

The lug 13 on the carriage 12 will then engage the switching lever of the switch 20 50 and will snap the same from the full-line position shown in the drawing to that indicated by dotted lines. This action completes a circuit through the switch 17, to place a lesser number of effective turns of the secondary winding 2 of the transformer 3 into 55 operation, thus causing the current to resume a normal value. However, it should be noted that, if the current now drops enough to cause the carriage 12 to again 60 make contact with the upper terminal 14, no change will occur since the switch 20 is no longer in such position that the switch 16 may be actuated. Moreover, it should be noted in connection with the subsequent 65 description of the other switches controlling

the effective turns of the transformer, that this safety relation always exists.

Assuming now that the current continues to increase by reason of the increasing temperature in the furnace, the carriage 12 will move still farther to the right, and the lug 13 will engage the switching lever 21 and move it from its full-line position to that shown by dotted lines. A circuit will now be completed through the coil operating the 75 switch 18, and the least number of effective turns of the secondary 2 of the transformer 3 will be connected to the furnace.

At this point, the temperature of, and the current passing through, the furnace should 80 become so stabilized that no further increase of temperature should occur. However, if a further undesirable increase does occur, and, if on account of the increasing danger of an abnormal current, it is desired to disconnect the furnace and allow it to cool slightly, the carriage 12, in its continued movement to the right, will cause the lug 13 to engage the member 24 and, since the switching members to which the member 24 85 is attached are provided with snap springs, a slight movement of the member 24 will cause the switches 20 and 21 to reassume the positions noted at the beginning of the description of the operation of the system. 95

Since all the switches 16, 17 and 18 are now open, no power will be fed to the furnace, and it will gradually cool. Moreover, since no current is now flowing into the furnace, the coil 11 will be deenergized, and 100 the motor will rotate in such direction as to cause the carriage 15 to travel toward the left. As soon as the carriage 15 makes contact with the contact member 14, the switch 16 will be closed and the furnace will again 105 be supplied with power.

The above set of conditions will result in the furnace again gradually heating up, but, in the interval of time elapsing between the engagement of the carriage 12 with the member 24 and its subsequent backward travel to the point where it will engage the contact member 14, the furnace will have had an opportunity to so far cool off, that the resistance thereof will be again decreased 110 and the current will, therefore, gradually 115 become stabilized.

While I have shown but one embodiment of my invention in which motor-controlled contact members are used, it is obvious that many modifications therein may occur to those skilled in the art, and I desire, therefore, that only such limitations be placed on my invention as are imposed by the prior art or by the appended claims. 125

I claim as my invention:

1. In a regulating system for an electric furnace, the combination with a transformer having a primary and a secondary winding, one of said windings being provided with a 130

plurality of taps, and switches for connecting said taps to the furnace, of motor-operated means for controlling said switches to maintain a substantially-constant current flow through the furnace and for opening the furnace circuit under certain conditions.

2. In a regulating system for an electric furnace, the combination with a transformer having a plurality of taps extending from it, and switches for connecting said taps to the furnace, of motor-operated means for operating said switches in accordance with the electrical conditions of said furnace, and means for opening the circuit of the furnace in case a current above normal value passes through the furnace for an extended period of time.

3. In a regulating system for an electric furnace, the combination with a transformer having a plurality of taps, and switches for connecting said taps to the furnace, of means comprising a motor for operating said switches to maintain a substantially-constant current flow through the furnace and means controlled by the motor for opening the furnace circuit under certain operating conditions.

4. The combination with an electric furnace and a transformer having an adjustable secondary winding for supplying power thereto, of means comprising a motor for controlling the power supplied to said furnace by said transformer secondary winding, said motor being operated in a direction corresponding to the amount of current passing through said furnace.

5. The combination with an electric furnace and a transformer having an adjustable secondary winding for supplying power thereto, of a motor operated in a direction corresponding to the current passing through said furnace, and contact-making means associated with said motor for controlling the number of effective turns in said secondary winding.

6. The combination with an electric furnace and a transformer having an adjustable secondary winding for supplying power thereto, of a motor operated in a direction corresponding to the current passing through said furnace, the shaft of said motor being provided with a worm thread, and a movable engaging member adapted to move along said worm shaft and operating

to change the effective turns of said transformer secondary winding.

7. The combination with an electric furnace and a transformer having an adjustable secondary winding for supplying power thereto, of a motor having a worm-threaded shaft, an engaging contact member adapted to move along said shaft, and switches controlling the effective turns of said transformer secondary winding, said switches being operated by said movable contact member.

8. The combination with an electric furnace and a transformer having an adjustable secondary winding for supplying power thereto, of a motor, a movable contact member controlled by the rotation of said motor, switches actuated thereby and controlling the effective turns of said transformer secondary winding; and a member operated by said contact member for controlling said switches whereby, upon the occurrence of an abnormal overload on said transformer secondary winding, no power is supplied to said furnace.

9. The combination with an electric furnace and a transformer having an adjustable secondary winding for supplying power thereto, of motor-operated means for gradually decreasing the number of effective turns of said transformer secondary winding as the current in said furnace tends to rise, said means being provided with a safety element to render said secondary winding completely ineffective when an abnormal load is imposed thereon.

10. The combination with an electric furnace and a transformer having an adjustable secondary winding for supplying power thereto, of motor-operated means for gradually decreasing the number of effective turns of said transformer secondary winding as the current in said furnace tends to rise, said means being provided with a safety element to render said secondary winding completely ineffective when an abnormal load is imposed thereon and being automatically operative to restore correct temperature conditions upon the cessation of said abnormal load.

In testimony whereof, I have hereunto subscribed my name this 2nd day of Dec., 1918.

RAYMOND T. PIERCE.
